METAL ROLLING MILL

Filed Nov. 3, 1928

UNITED STATES PATENT OFFICE

EWALD RÖBER, OF DUSSELDORF, GERMANY

METAL ROLLING MILL

Application filed November 3, 1928, Serial No. 317,104, and in Germany March 14, 1928.

Devices have been proposed for conveying the work piece in tube rolling (Perrins process), in which the conveying movement is effected through the medium of a liquid column which is shifted by means of a movable pressure member. We know also how in such devices that end of the container nearest the rolls, and which end receives the liquid column, is imperfectly shut off from the remaining space in the container, causing at this point towards the end of the conveying movement the development of a temporary increase in pressure above atmospheric and thus producing a retarding action upon the connecting rod. It has been further proposed to choke the liquid column in devices of this kind during the shifting movement thereby to reduce the conveying pressure towards the end of the conveying movement.

The present invention relates to an improved device of the character set forth, the principal object of the invention being to provide means for effecting a temporary pressure above the atmospheric pressure at the end of the liquid container nearest the rolls and thereby produce a more efficient and precise retarding action of the connecting rod, a further object of the invention being to provide a device for retarding the connecting rod at the end of its return movement. Because of the fact that the rolls impart to the rod during the rolling process such great kinetic energy that at the termination of the rolling operation the movement of the connecting rod does not immediately cease. This continuation of the movement of the rod is disadvantageous because of the loss of time consumed in the continued travel of the rod and its return over the unnecessarily elongated path. The avoidance of this continuation of the movement of the rod permits an increase of the working speed about 30 percent.

The accompanying drawing shows diagrammatically a longitudinal section of one embodiment of the present invention.

Mounted for reciprocation in a casing *a* is a rod *b* having a piston *c* secured at its inner end. A cylinder *e* provided with a suitable cover *e'*, in which cylinder a float *f*

is easily reciprocable, is attached to a projection *d* of the casing *a*. The float *f* is disposed in the cylinder *e* and is provided with an extension *g* adapted when moved downward, to close the communicating opening *h* between the cylinder *e* and the projection *d*, said extension fitting said opening with a little play. The front part of the casing forms a cylindrical chamber *i* of less diameter than the rear part, said front and rear parts communicating with each other by way of a channel *k* which channel is of the same diameter as the piston *c*. Mounted in chamber *i* is a buffer spring *l* of any kind, which normally retains a plate *n* having a number of holes *m* against the end of the channel *k*, said plate being loosely mounted on the connecting rod *b*. Whenever the float *f*, *g* and the piston *c* have descended to their lower positions shown in dotted lines, the following chambers are formed: the working chamber I, the choking chamber II, the retarding chamber III and the pressure chamber IV. The last named chamber contains air or gas of a pressure amounting to about twenty-five atmospheres, the other chambers being filled with water. The chamber III communicates with the chambers I and II by way of pipes equipped with check-valves *o* and *p* respectively. The casing *a* is closed at its rear end by means of a threaded plug *q* having a ring shaped groove *r* in its end face for the reception of the correspondingly formed flange *s* of the piston *c* on the rearward movement of the piston. A check valve *t* finally controls the communication between the chamber I and chamber II, said valve opening towards chamber II.

The operation of the device is as follows: The float *f*, *g* under the pressure of the gas in chamber IV, is constantly urged downward, thus transmitting said pressure to the water in the chambers therebelow, and owing to the fact that the piston *c* has a larger area exposed to the pressure of the water at the left or rear side than at the right side thereof, the piston begins to move toward the right, and with it the rod *b*. This forward movement carries that portion of rod *b* which is of smaller diameter into the chamber I, while a

corresponding length of the portion of rod *b* of larger diameter is moved out of chamber I and into chamber III. The water-capacity of chamber I is thus increased, and consequently the water passes from chamber II to chamber I, thereby permitting the float *f* to move downward under pressure of the gas in chamber IV. At the time the piston *c* has progressed about two-thirds of its travel toward the right the valve portion *g* of the float has begun to throttle the communicating channel *h* between the chambers II and I. The piston *c* and its rod *b*, however, continue to move forward because of the momentum stored therein. The water-capacity of chamber I thus becomes larger as a greater length of that portion of rod *b* of smaller diameter takes the place of a corresponding length of the portion having the larger diameter in chamber I, and since the water cannot pass from chamber II with sufficient rapidity to fill the increased water-space in chamber I the pressure on the piston *c* toward the end of its stroke is actually decreased, so that at the time the piston *c* enters the channel *h* its momentum is practically spent. If the diameters of the rod *b* at the opposite sides of the piston *c* and the length of the portion *g* of the float are in correct ratio, the piston *c* will come to rest in abutting relation with the disc *n*, any tendency of the piston to continue its travel being resisted by the water confined in chamber III. The disc *n* is normally maintained under the tension of its spring in the position shown in the drawing, the provision of this disc and the valved bypasses *o* and *p* being merely a safety measure, since in the normal operation of the device the disc will not be actuated. However, if for any reason the piston *c* should continue to move toward the right against the tension of the spring *l*, the water in chamber III will be forced through valve pipe *p* in chamber II, it being understood that even when the member *g* has completely closed the channel *h* the valved pipe *p* is still in communication with chamber II, so that the pressure on the water in chamber III is transmitted to chamber II below the float, thus causing the same to rise and compress the gas in chamber IV. As soon as the connecting rod *b* commences its backward movement and the piston *c* moves away from disc *n* the pressure on the water in chamber III is removed suddenly. However, owing to the provision of the valve *o*, no vacuum will be formed in chamber III because the water in chamber I will immediately pass over, so that by the time the piston has left the channel *h* the pressure in chambers I and III is completely equalized. In like manner, the valve *t* serves to equalize the pressure in chambers I and II by permitting the water to pass from chamber I to chamber II in case the pressure in chamber I is higher than that in chamber II. When the piston

arrives at the end of its backward movement the flange *s* enters the groove *r* of the plug *q*, whereupon the further movement of the piston is retarded by the pressure of the water between it and said plug. By reason of the threaded connection of the plug *q* with the housing, the said plug may be readily adjusted to permit longer or shorter strokes of the piston *c* to meet the requirements of varying rolling operations. This adjustability of the plug renders possible the retardation of the rearward movement of the piston as above described, since it insures the positioning of the plug to correspond with the exact end position of the rod *b*.

The forward end of the rod *b* extends beyond the end of the casing and forms a feed rod to which is attached the usual mandrel carrying the work *w* that is to be operated on by the rolls *y*, in the well known manner.

What I claim is:

1. In a rolling mill, the combination of a casing having a horizontal cylindrical portion and a vertical cylindrical portion, said portions together forming a pair of chambers of different diameters and communicating by a channel of smaller diameter than either of said chambers, a reciprocable mandrel feed bar, a rod carried by said feed bar for reciprocation in said horizontal portion of the casing, a piston secured on that portion of the rod normally within the chamber of larger diameter, said piston having the same diameter as said channel and provided with an axially extending flange at one end thereof, a plug threaded in the outer end of said enlarged chamber and having in its inner end face a circular groove adapted to receive said flange, a cylindrical extension mounted on said vertical portion of the casing and forming a chamber communicating through a channel of smaller diameter with the larger chamber in the casing, a movable member disposed in said cylindrical extension and dividing its chamber into an upper chamber and a lower chamber, said upper chamber containing a fluid under pressure and all of the remaining chambers being filled with an incompressible fluid, thereby to create in all of the lower chambers a temporary pressure above atmospheric, said movable member having an extension adapted to enter said last communicating channel and close the same thereby to discontinue said pressure on the fluid in said lower chambers.

2. In a rolling mill, the combination of a casing having a horizontal cylindrical portion and a vertical cylindrical portion, said portions together forming a pair of chambers of different diameters and communicating by a channel of smaller diameter than either of said chambers, a reciprocable mandrel feed bar, a rod carried by said feed bar for reciprocation in said horizontal portion of the casing, a piston secured on that portion of the

- rod normally within the chamber of larger diameter, said piston having the same diameter as said channel and provided with an axially extending flange at one end thereof, a 5 plug adjustably secured in the outer end of said enlarged chamber and having in its inner end face a circular groove adapted to receive said flange, a cylindrical extension mounted on said vertical portion of the casing and 10 forming a chamber communicating through a channel of smaller diameter with the larger chamber in the casing, a movable member disposed in said cylindrical extension and dividing its chamber into an upper chamber 15 and a lower chamber, said upper chamber containing a fluid under pressure and all of the remaining chambers being filled with an incompressible fluid, thereby to create in all of the lower chambers a temporary pressure 20 above atmospheric, said movable member having an extension adapted to enter said last communicating channel and close the same thereby to discontinue said pressure on the fluid in said lower chambers.
- 25 3. In a rolling mill, the combination of a casing having a horizontal cylindrical portion and a vertical cylindrical portion, said portions together forming a pair of chambers of different diameters and communicating by 30 a channel of smaller diameter than either of said chambers, a reciprocable mandrel feed bar, a rod carried by said feed bar for reciprocation in said horizontal portion of the casing, a piston secured on that portion of the rod normally within the chamber of larger 35 diameter, said piston having the same diameter as said channel and provided with an axially extending flange at one end thereof, a plug threaded in the outer end of said enlarged chamber and having in its inner end face a circular groove adapted to receive said flange, a cylindrical extension mounted on said vertical portion of the casing and forming a chamber communicating through a channel of smaller diameter with the larger chamber in the casing, a movable member disposed in said cylindrical extension and dividing its chamber into an upper chamber and a lower chamber, said upper chamber containing a fluid under pressure 40 and all of the remaining chambers being filled with an incompressible fluid, thereby to create in all of the lower chambers a temporary pressure above atmospheric, said movable member having an extension adapted to enter said last communicating channel and close the same thereby to discontinue said pressure on the fluid in said lower chambers, a perforated circular plate loosely mounted on that portion of said rod normally within the chamber 45 of smaller diameter, a spring in said chamber normally retaining said plate in position to close the communicating channel between said chambers, and valved pipes forming bypass communications between said chamber of smaller diameter and the chamber of larger diameter and between said chamber of smaller diameter and the lower chamber in said cylindrical extension.
- 50 In testimony whereof I have affixed my 55 signature.
